UNITED STATES PATENT OFFICE.

JAMES S. SMITH, OF MIDDLETOWN, CONNECTICUT.

BUTTON.

SPECIFICATION forming part of Letters Patent No. 272,491, dated February 20, 1883.

Application filed October 21, 1882. (No model.)

To all whom it may concern:

Be it known that I, JAMES S. SMITH, of Middletown, Middlesex county, in the State of Connecticut, have invented certain new and useful Improvements in the Construction of Buttons, of which the following is a specification.

My improved button is of the class in which the attachment to the garment is effected by passing the needle and thread many times out and in through the button; but, instead of passing the thread up through one hole and down through another, I effect the fastening by passing the thread up and down or out and in through the same hole, providing a cross-bar of metal or other strong material bridging across the hole, and serving to receive the thread and to hold the button. I can make the improved button of a great variety of materials. I will describe the main body as wood, preferably maple. The surface is finished by japaning or enameling. The cross-bar I will describe as brass.

The following is a description of what I consider the best means of carrying out the invention.

The accompanying drawings form a part of this specification.

Figure 1 is a face view; Fig. 2, a cross-section, and Fig. 3 a section on the line S S in Fig. 2. The above figures show the button after the cross-bars have been inserted and before they have been bent. Fig. 4 shows the die by which the bending of the cross-bars is effected. Fig. 5 is a cross-section through the completed button. The remaining figures show modifications. Fig. 6 shows the button formed without an eyelet, and having the cross-bars introduced near the face of the button. Fig. 7 is a face view, and Fig. 8 a cross-section showing a modification in which there are two holes. Fig. 9 is a face view of a modification, showing only one cross-bar.

Similar letters of reference indicate corresponding parts in all the figures where they occur.

A is the body of a button, produced by hand or machinery in the form of an annulus or flat ring, with a small-sized hole, a, in the center. Any fine-grained wood may be employed with the grain running in any direction. I prefer maple with the grain running in the plane of the button.

B is an eyelet, of brass or other suitable material, inserted in the hole a, and flanged so as to be retained in the button in the ordinary manner. The hole a is preferably formed with a proper enlargement on each face of the button to receive the flanges of the eyelet B and give a flush surface.

I insert in or near the middle of the thickness of the button two lengths, D, of brass wire, at right angles to each other. They are inserted only a little out of the same plane. Each extends from near one edge of A radially inward to and across the eyelet B, and thence extends outward through the body A again nearly but not quite to the opposite edge. The holes to receive these wires are previously bored by a drill inserted from one edge, taking care to use a tool which can drill both the wood and the brass. The wires are forced in from the edge, and should fill the hole so tightly that it requires some force, by hand or by machinery, to drive them home. I then, by a suitable die, M, inserted from what is to be the outer face of the button, bend downward the wires D where they extend across the hole a. The female die N should be of such form as to enter the hole a from the back face of the button and support the cross-bars or cross-wires D at the edge of the hole a, thus relieving the wood from strain and allowing the bend to be formed in the middle portion only. This gives each wire D a crimp or bend, D', which prevents its ever working out under any circumstances, and also allows the thread by which the button is to be held to be better sunk and concealed in the body of the button. The act of bending the cross-bars D tends to draw inward the ends thereof, so that there is a little vacancy left at each end. This insures that the ends of the cross-bars are effectually protected and concealed within the body of the button. The buttons thus prepared are immersed in suitable varnish and baked. The varnish fills any vacant space remaining in the holes in which the cross-bars D were inserted. It also strengthens the body of the wood and strongly cements the cross-bars to the wood. The heat of the baking, by slightly shrinking the wood, also increases the tightness as well as the strength with which the cross-bars D are held.

E in Fig. 5 represents the surfacing of hard

material, generally termed "japan" or "enamel," which forms a finish for the exterior and fills the holes through which the cross-bars had previously been inserted.

5 The improved button is attached to a coat or other garment in the obvious manner, the needle and thread being passed up and down through the hole *a*, so as to bridge across over the portion *D* of the cross-bars, in the same 10 manner as the threads ordinarily hold buttons by bridging across over a portion of the body of the button.

Modifications may be made in many of the 15 details without departing from the principle or sacrificing the advantages of the invention. I can dispense with the eyelet *B*, and by inserting the wires *D D'* in the wooden annulus *A* alone, and japanning, make a very satisfactory button, which can be sold at a small 20 price. This construction is shown in Fig. 6. I can dispense with the form of die *N* shown and leave the cross-bars *D* unsupported, except by the wood *A*, when the die *M* comes down to effect the bending. I can dispense with the bend *D'* and allow each wire 25 to stand straight in the button. Instead of inserting the cross-bars in the middle of the thickness, I can set them nearer the front face of the button, and thus take hold of a greater 30 thickness of the wood to resist the force tending to rend the cross-bars away from the button. This construction is shown in Fig. 6.

I can realize a good portion of the benefits 35 of the invention by using only one cross-bar *D D'*. When this is done I prefer to insert it at right angles to the grain of the wood. This is shown in Fig. 9.

I propose in the manufacture of large buttons for heavy overcoats, horse-blankets, &c., 40 to employ bodies *A* having two holes *a*, each crossed by two wires or cross-bars *D*, and having the bend *D'*. This construction is shown in Fig. 7.

I esteem it a great advantage in my button 45 that the body *A* is in a single piece, and that the cross bar or bars *D* are inserted by a thrusting force from the edge. There is nothing tending to force out the cross bar or bars. My experiments indicate that there is little 50 risk of looseness when they are fitted with proper tightness, even without the japanning or the bending.

I claim as my invention—

1. That improved method of forming an attaching eye or loop to a solid button which 55 consists in making a transverse perforation into the body of the button, which shall intersect the central opening, and inserting a cross-bar therein, then bending the cross-bar downward in the central opening to form a 60 loop or eye, all substantially as set forth.

2. The body *A*, formed of a single piece, having a central hole, *a*, and a transverse hole or holes made from the circumference, in combination with one or more cross-bars, *D*, the 65 latter being supported in the transverse hole or holes and extending across the hole *a*, as herein set forth.

3. A button composed of a body, *A*, having a hole, *a*, an eyelet, *B*, and one or more cross-bars, *D D'*, as herein specified. 70

4. A button composed of a wood body, *A*, having a hole, *a*, eyelet *B*, two cross-bars, *D*, each bent as indicated at *D'*, and japanned or enameled, as herein specified.

In testimony whereof I have hereunto set 75 my hand, at Middletown, Connecticut, this 18th day of October, 1882, in the presence of two subscribing witnesses.

JAMES S. SMITH.
